UNITED STATES PATENT OFFICE.

HENRY H. CHASE, OF JAMESTOWN, NEW YORK.

SOCKET-WRENCH CONTAINER.

Application filed October 4, 1921. Serial No. 505,273.

To all whom it may concern:

Be it known that I, HENRY H. CHASE, a citizen of the United States, residing at the city of Jamestown, in the county of Chautauqua and State of New York, have invented certain new and useful Improvements in Socket-Wrench Containers, of which the following, taken in connection with the accompanying drawings, is a specification.

The invention relates to containers for tools; and the object of the improvement is to provide a simple and strong sheet metal socket wrench container which provides a locking element out of a part of the tool so that a plurality of different size socket wrench heads may be retained in small space for use in automobile tool kits and similar places; and the invention consists in the novel features and combinations hereinafter set forth and claimed.

In the drawings, Figure 1 is a perspective view of the socket wrench container with the handle in position locking the wrench heads in the container and locking itself within the container ends by means of the resilient frictional ball fasteners in each end of said handle. Fig. 2 is an end elevation of the wrench container with the locking wrench handle in position and showing the preferred construction of the container, the locking bar handle being shown in section to show the construction of the spring ball fastener. Fig. 3 is a crosswise sectional view showing the cover on said container, said cover being locked in position by said wrench handle. Fig. 4 is a top plan view of the wrench container with the socket wrench heads therein, the locking bar handle being shown in dotted outline. Fig. 5 is a side elevation of said locking bar handle. Fig. 6 is a sectional view of the preferred construction of the socket wrench head with the angular end of the bar handle securely held therein by means of the spring ball fastener. Fig.

7 is a perspective view of an end portion of the container with cover thereon, the cover showing the hexagonal-shaped opening in the end to receive the bar handle of the socket wrench heads. Fig. 8 is a plan view of the socket end for the insertion of the hexagonal-shaped handle bar.

Like characters of reference refer to corresponding parts in the several views.

55 The numeral 10 designates the container

which is preferably made of sheet metal and has the bent-up ends 11 and sides 12.

The ends 11 have the lugs 13 at each side to extend around the bent-up sides 12, and the sides 12 have the lugs 14 which bend 60 around the outer sides of the ends 11, thereby holding against one another at each corner and making a firm, strong and durable container which securely holds the heavy wrench socket heads, said container being 65 shaped as to its dimensions so that the wrench socket heads 15 are easily received therein.

In order to lock the wrench socket heads 15 in position, the hexagonal-shaped bar 70 handle 16 is received through the similarly shaped openings 17 in each of the ends 11 so that the long end of the angular handle bar 16 may be inserted through the hexagonal-shaped holes 17 a spaced distance above 75 the socket wrench heads 15, thereby securely holding the wrench heads 15 in said container.

The socket wrench handle 16 is locked in the openings 17 of the container 10 by means 80 of the frictional ball fasteners 18 which consist of a spring and ball inserted in a round hole 19 in each end of the bar 16 and serve the double purpose of frictionally holding in the hexagonal-shaped opening 20 in the 85 wrench sockets 15 and also holds said handle bar 16 in the openings 17, pressing easily through said openings 17 and preventing the withdrawal of the bar without greater pressure than would naturally come upon said 90 bar, it also being necessary to prevent the bar 16 easily sliding through the hexagonal-shaped holes 17.

The bar 16 is preferably given the angular shape by the right angle bend 21 so that 95 a stronger leverage can be obtained by use of the short end where there is room for said leverage by turning the long end of the bar. Said long end is used in the wrench socket when it is necessary to reach into deep recesses with the socket wrench.

The sockets 15 are preferably made with the hexagonal-shaped holes 22 for the hexagonal nuts, and 20 for the end of the handle bar 16 in the opposite ends of the sockets, 105 a partition 23 being left between said hexagonal-shaped openings 20 and 22 with holes 24 through said partition in order to clean the wrench sockets 20 and 22 of any liquids or dirt.

The cover 25 is shaped to fit over the ends 11 and has the hexagonal-shaped holes 26 through the ends of the same which coincide with the holes 17 in the main portion 5 of the container 10 so that the handle bar 16 will pass readily through the hexagonal-shaped holes 17 and 26, thereby firmly holding the cover 25 in place upon the ends 11 and forming a complete cover closure for 10 the container 10.

What is claimed as new is:

1. In a container for a compound tool having certain of the elements of the tool packed therein, a locking element for retaining said elements within the container comprising a part of said tool.
2. In a container for a compound tool having elements with certain of the latter packed therein, means comprising a part 20 of the tool common to all of said certain elements and engaged with each of the latter for retaining same within the container.
3. In a container for a compound tool having elements with certain of the latter packed therein, a cover for the container, and means comprising a part of the tool engaged with each of said certain elements and with the cover for holding said certain elements in packed position in the container 30 and for holding the cover on the container.
4. In a container for a compound tool having elements with certain of the latter packed therein, a cover for the container, and means to hold the cover on the container comprising a part of the tool.
5. A multiple socket wrench container comprising a receptacle having ends extending above the sides of said receptacle, said ends having holes therethrough a spaced distance above the sides of said receptacle, a 40 cover struck up from sheet metal fitting over said upwardly extending ends, said cover having holes therethrough coinciding with the holes through said upwardly extending ends, and a tool handle corresponding in shape to said holes to be received therethrough in locking engagement.
6. A multiple socket wrench container comprising a receptacle, oppositely projecting lugs on the sides and ends of said receptacle to hold against one another, said ends having hexagonal-shaped holes therethrough a spaced distance above the wrench sockets in said container, a hexagonal-shaped handle bar for said sockets fitting in said hexagonal-shaped holes to be received therethrough in locking engagement over 50 said wrench sockets, and resilient frictional fastenings in the ends of said handle bar to lock said handle bar in said hexagonal openings in said container ends.
7. A multiple wrench container struck up from sheet metal having its end portions extending upwardly above the socket wrench parts, lugs on the sheet metal sides and ends

of said container to interclasp and hold each corner, said upwardly extending ends having angular-shaped holes therethrough, a similar shaped handle bar for said wrench sockets, insertable through said angular-shaped holes, spring ball fasteners in the opposite ends of said bar to permit insertion of said bar through said angular shaped openings in said upwardly extending ends to lock said wrench sockets in said container 75 by locking said handle bar in said upwardly extending ends, said fasteners also locking the ends of said handle bar in said wrench sockets.

8. A multiple wrench container struck up 80 from sheet metal having its end portions extending upwardly above the socket wrench parts, lugs on the sheet metal sides and ends of said container to interclasp and hold each corner, said upwardly extending 85 ends having hexagonal holes therethrough, a hexagonal handle bar for said wrench sockets having spring ball fasteners in its opposite ends to permit insertion of said bar through said hexagonal openings in 90 said ends to lock said wrench sockets in said container and lock said handle bar in said upwardly extending ends, said fasteners also locking the ends of said handle bar in said wrench sockets, a cover fitting over said upwardly extending ends, said cover having hexagonal - shaped openings therethrough coinciding with said hexagonal-shaped openings in said upwardly extending ends to receive said handle bar through said openings in said upwardly extending ends and said openings in the ends of said cover to lock the wrench sockets in said container and to lock said cover on said container.

9. In a container for compound tools, a receptacle having certain of the elements of the tool packed therein, locking means for retaining said elements in packed position within the receptacle comprising a part 105 of the tool, means carried by the receptacle to support said locking means, and means carried by the locking means for latching engagement with the supporting means to hold the locking means in position.

10. In a container for compound tools, a receptacle having certain of the elements of the tool packed therein and having apertured parts, and locking means for retaining said elements in packed position within the receptacle comprising a part of the tool 110 engaged in the apertures of said apertured parts.

11. A multiple socket wrench container including a receptacle for supporting the sockets by engagement with one end of the latter, and apertured parts on the container for receiving the wrench handle and disposed so as to cause the handle to engage with the opposite ends of the sockets.

12. A multiple socket wrench container 130

- including a receptacle for supporting the sockets by engagement with one end of the latter, apertured parts on the container for receiving the wrench handle and disposed so as to cause the handle to engage with the opposite ends of the sockets, and means carried by the handle to latch the latter in its locking position.
13. A multiple socket wrench container including a receptacle for supporting the sockets by engagement with one end of the latter, apertured parts on the container for receiving the wrench handle and disposed so as to cause the handle to engage with the opposite ends of the sockets, said handle having a right angular end which limits movement of the same into operative position.
14. A multiple socket wrench container including a receptacle for supporting the sockets by engagement with one end of the latter, apertured parts on the container for receiving the wrench handle and disposed so as to cause the handle to engage with the opposite ends of the sockets, and means carried by the handle to latch the latter in
- its locking position, and for engaging in the wrench sockets to latch the handle to the latter.
15. In a container for a compound tool having certain of the elements of the tool packed therein, a locking element for retaining said elements within the container comprising a part of the tool, and means for latching said part of the tool in locking position.
16. In a container for a compound tool having certain of the elements of the tool packed therein, a locking element for retaining said elements within the container comprising a part of the tool, and means for latching said part of the tool in locking position, said latching means being also formed to engage said certain elements to interchangeably latch same to said part of the tool.

In testimony whereof I have affixed my signature in the presence of two witnesses.

HENRY H. CHASE.
